UNITED STATES PATENT OFFICE.

PATRICIO L. EBARLE, OF SAN FRANCISCO, CALIFORNIA.

DESIGN FOR A CONTAINER FOR TABLE SERVICE.

Application filed February 23, 1927. Serial No. 20,848. Term of patent 3½ years.

To all whom it may concern:

Be it known that I, PATRICIO L. EBARLE, a citizen of the Philippine Islands, and residing in San Francisco, county of San Francisco, and State of California, have invented a new, original, and ornamental Design for a Container for Table Service, of which the following is a specification, reference being had to the accompanying drawing, forming part thereof, and in which the figure is a perspective view of a container for table service showing my new design.

I claim:

The ornamental design for a container for table service, as shown.

PATRICIO L. EBARLE.
